UNITED STATES PATENT OFFICE.

FRANK WILCOMB, OF NORRISTOWN, PENNSYLVANIA, ASSIGNOR TO WILDMAN M'F'G CO., OF NORRISTOWN, PENNSYLVANIA, A CORPORATION OF PENNSYLVANIA.

DETACHABLE PRESSER FOR SPRING-BEARD NEEDLES.

1,255,259.

Specification of Letters Patent. Patented Feb. 5, 1913.

Application filed August 14, 1913. Serial No. 114,805.

To all whom it may concern:

Be it known that I, FRANK WILCOMB, a citizen of the United States, and a resident of Norristown, Pa., have invented certain new and useful Improvements in Detachable Pressers for Spring-Beard Needles, of which the following is a specification.

The invention is applicable to spring beard needles of various types, whether direct fed or sinker fed on machines in which the needles and coöperating elements are operated independently or machines having needles fixed in a bar and operated simultaneously or a machine in which the needles are fixed in a suitable support and a presser is employed movable along the needle row. The preferred form of machine is the circular type having independently operated needles and the following description is presented in connection with a machine of that type.

The invention is applicable to machines having sliding elements, such as web holders or sinkers coöperating with the needles or to machines in which the elements, one or more, are pivotally mounted.

The invention consists in the features and combination and arrangement of parts hereinafter described and particularly pointed out in the claims.

In the accompanying drawings;

Figure 1 is a vertical sectional view of a part of a needle cylinder with my improved presser ring in place, the machine shown being one in which the yarn is fed direct to the needles without the employment of sinkers.

Fig. 2 shows in section the ring or bed for the presser units detached.

Fig. 3 is a detached view of one of the presser units.

Fig. 4 is a view of the pressing unit with a machine having web holders and sinkers.

Fig. 5 is a view of the beds of Fig. 4 for the needles, sinkers and web holders and with the web ring detached.

Fig. 6 is a plan view of the web holder bed with some of the presser units inserted therein and some of the seats for these pressers being empty.

Figs. 7, 8 and 9 are views of the pressing unit.

Referring to Figs. 1, 2 and 3, 1 indicates a needle cylinder having the usual guiding

slots or grooves for the spring beard needles. Supported on this cylinder is a web ring 2 55 and supported on a shoulder 3 of this web ring is an outside presser ring 4, this presser ring holding removably the presser units and while the attachment of the presser units to this ring may be accomplished in 60 various ways, in the particular construction shown the presser ring or bed is slotted vertically at 5 on its outer face and it may be slotted across its upper face. The presser units are preferably of the form shown in 65 the detached view, Fig. 3, and consist of bits or pieces 6 of generally inverted U-shape having depending inner and outer prongs.

These units are adapted to fit astride of the ring or bed 4 with the outer prong inserted in one of the vertical slots 5 of the ring or bed, while the inner prong fits against the inner surface of the ring and the lower edge of the main body of the bit or piece between the prongs fits on the upper 75 surface of the ring. The presser unit may be held to the ring in various ways, for instance, by friction or by a wire surrounding the series. I have shown however, spring bands 7 fitting in notches in the presser units 80 and in notches or grooves in the outer surface of the walls between the vertical slots of the presser holding ring. The pressers have a rounded upper inner corner at 8 and their inner faces are grooved vertically to 85 receive the needle beards, this grooved construction serving to aline up any beards that may have become displaced laterally and cause them to perform their proper functions. The presser holding ring may be held 90 in various ways but in Fig. 1 I have shown it simply as resting on the shoulder 3, whereon it is held by the upper part of the web holder which overlies and rests upon the presser ring. The web holder has an inner 95 prong forming the fabric supporting surface and these inner prongs slide in shallow slots formed in the web ring. The web holders have also a lower prong slidable in a groove 9 formed in the outer surface of 100 the web ring, the stems of the web holders sliding on a suitable bed 9^a and their butts 10 being engaged by a suitable cam held by a cap plate 11.

The construction described by which the 105 web holders are held in their proper plane

by the inner prong and the outer stem serves also as a means for holding the presser ring to its seat, because as above stated, the upper main portion of the web holder overlies and 5 works upon the upper surface of the presser ring. The inner grooved face of the presser unit may be arranged at an inclination to the normal line of movement of the needle as in Figs. 1 and 4 in order that as the needle 10 draws down it will move into a gradually contracting space, the needle during the pressing action being deflected outwardly from its normal plane, so that as it retracts its beard will be forced against the 15 presser unit and will thereby be closed to pass through the old loop and by reason of the inclined relation of the presser surfaces to the normal plane of the needle beard the beard will be pressed during this retracting 20 stroke to an extent which will prevent any tendency for the beard to burst the loop through which it is passing, this pressing action being maintained in proper degree because of the inclined relation mentioned, 25 even after the needle is free from the inside presser device which deflects it from its normal plane. This inside presser device *a* may be in the form of a wheel or other form of device to act against the backs of the needles 30 and deflect them outwardly. The inclined relation of the presser surface to the normal plane of movement of the needle also affords a comparatively large space at the top of the needle cylinder or web ring and between 35 the same and the presser device or unit to receive the nose of the needle without crimping the same. The inclined relation between the surface of the presser and the normal plane of movement of the needle may be secured either by tapering the needle cylinder 40 and using a presser ring or a series of presser elements of substantially cylindrical form or arrangement or by using a needle cylinder of cylindrical form throughout and tapering 45 downwardly the presser ring made up of the series of presser bits. Any one of the presser bits can be quickly removed for repair and replacement by simply drawing it upwardly from its seat. The presser units 50 may be formed of hardened material, such as steel, thus securing great durability and adapting the construction to fine gage machines, and the presser bits not only perform the function of pressing the needle beards 55 but they perform the function of guiding the web holders, answering the purpose of the usual guiding walls which are left upstanding by the customary slotting operation, this slotting operation of course in a 60 fine gage machine leaves thin upstanding walls and these being of soft material are liable to become bent or displaced, whereas with my present construction in which the hardened steel bits or pieces are employed a 65 very thin piece suited for the finest gages of

machines will afford ample stiffness against lateral displacement.

Referring to Figs. 4, 5, 6, 7 and 8 I show in Fig. 4 an arrangement in which web holders and sinkers are employed and in Fig. 70 5 the beds for these parts are illustrated.

The sinkers and web holders may assume various forms and may be operated in various ways but for convenience of illustration I have shown an interlocking form of sinker 75 and web holder, which is made the subject matter of another application, together with certain other features disclosed in these figures, No. 114,804, August 14, 1916.

The web holders in this instance, are supported by a bed 5^a which has a machined or turned upper surface upon which the web holders move, said web holders being guided by the presser bits 6^a, which besides performing their beard pressing functions also 80 serve as the guiding walls for the web holders and sinkers. These presser bits like those first described have inner and outer prongs and they are seated by the outer prong fitting in the outer vertical slot of the 90 web holder bed, the main body of the bit or presser piece fitting down in a radial slot 12 formed in the top of the bed, whereas the inner prong fits against the inner face of the bed. This bed also furnishes the support for 95 the sinkers and while sliding sinkers may be employed instead of pivoted sinkers I show for convenience the pivoted arrangement, the pivots of the sinkers resting in grooves or seats 13 formed in the upper edges of the 100 walls 14 left by slotting the bed to receive the shanks of the sinkers. The sinkers are also guided by their substantially horizontal arms 15 working in slots of a cage 16 and the cam path is indicated at 17. The combined web holder, presser bit, and sinker bed rests upon a shoulder 18 of the cylinder and a clamp screw 19 pressing a soft metal plug 20 against the walls of the cylinder wall holds the cage and the combined web holder 110 and sinker bed in place.

It will be understood that the features described in connection with the first form of the invention relating to the web holders serving to prevent circumferential displacement of the outer presser ring or bar may be employed in connection with the form shown in Fig. 4.

It will further be understood that sinkers of some form may be used in connection with 120 the form of invention first described, for instance, a sliding sinker may be employed with the form of invention first illustrated and described.

A cap piece 21 overlies the sinkers 22, and 125 is slotted at 23 on its under side for guiding the same.

Certain features disclosed herein are also disclosed in application originally filed by me August 14, 1916, No. 114,804, Renewal 130

Number 180,018, and certain features which are not claimed herein are claimed in said other application.

What I claim is:—

- 5 1. In a spring beard needle knitting machine, needle beard pressing means comprising means to act on the backs of the needle bears are pressed when so deflected working plane, and means against which the 10 needle beards are pressed when so deflected consisting of members which when in working position are fixed and a bed for said members having seats therefor, said seats individually acting to hold their corresponding members upright independently of the 15 adjacent members and from which seats the members are individually removable, substantially as described.
2. In a spring beard needle knitting machine, a needle beard pressing means comprising a support, independently removable pressing units held stationary on said support when in working position, and having pressing faces arranged at an inclination and convergent downwardly to the normal plane of the needles, said pressing units being grooved on their said convergent pressing faces and means for deflecting the needles against said fixed units, substantially as described.
3. In combination in a spring needle knitting machine, needles and beard pressing means comprising independent bits or pieces, each of said bits being stationary in action but independently removable and each having a pressing surface arranged at an inclination to the normal working plane of the needles to maintain control of the beard from the beginning of the pressing action substantially throughout the retracting movement of the needle and a support for the said pieces or bits and means acting upon the backs of the needles to deflect them outwardly, substantially as described.
4. In combination in a spring beard needle knitting machine, a slotted ring outside the needle row having guides for web holders, consisting of individually removable elements serving as pressers for the needle beards, said elements being seated in the slotted ring, a needle cylinder or web ring having slots for the guidance of the web holders and web holders extending from between the presser elements on the said ring 50 into said slots, whereby the ring will be held against circumferential movement relative to the needle cylinder or web ring, substantially as described.
5. In combination in a spring beard needle knitting machine, needles, web holders, a supporting member and presser units held outside the needle row by said supporting member immovably and against lateral displacement said presser units being independently removable, and presser means in-

side the needle row to deflect the needles outwardly, substantially as described.

6. In combination in a spring beard needle knitting machine, spring beard needles, a slotted supporting member and a series of 70 presser units fitting removably in the slots in the supporting member and held immovably by frictional contact with the walls of said slots, substantially as described.

7. In combination in a spring beard needle 75 knitting machine, spring beard needles, a supporting member and pronged presser units individually seated and held immovably on said supporting member by the grip of their prongs, said prongs fitting the supporting member removably while the latter maintains its position, substantially as described.

8. In combination spring beard needles, a supporting member slotted vertically and 85 presser units having prongs to fit said vertical slots, said presser units being individually removable, substantially as described.

9. In combination spring beard needles, a supporting member, a series of presser units, 90 each formed with an inner and an outer prong, said supporting member being slotted to receive one of said prongs, substantially as described.

10. In combination spring beard needles, 95 a supporting member, presser units having inner and outer prongs, said presser units resting with their prongs astride the supporting member and the inner prongs having pressing surfaces for the needle beards, 100 substantially as described.

11. In combination spring beard needles, web holders, a bed therefor having a machined or turned upper surface for guiding the web holders and inserted bits or pieces 105 supported by said web holder bed at said machined surface and extending upwardly therefrom between the web holders and furnishing lateral guidance therefor, while the machined surface serves as guiding means 110 for the bottom edges of the web holders, substantially as described.

12. In combination spring beard needles, web holders, a bed therefor having a machined or turned upper surface for guiding 115 the web holders and inserted bits or pieces supported by said web holder bed at said machined surface and extending upwardly therefrom between the web holders and furnishing lateral guidance therefor, while the 120 machined surface serves as guiding means for the bottom edges of the web holders, said bits or pieces being individually removable, substantially as described.

13. In combination spring beard needles, 125 instruments working in the spaces between the needles, a bed having a curved machined top on which said instruments move, and inserted pieces in said bed at said machined surface extending up therefrom between the 130

- said instruments to guide them laterally while the curved bottom edges of said instruments slide on the machined surface, substantially as described.
- 5 14. In combination spring beard needles, sinkers, web holders, a single bed for said sinkers and web holders having a machined upper surface for guiding the web holders, bits or pieces held stationary by but removable from the bed and extending between the web holders to guide them, said sinkers interlocking with the web holders for operating them, and closely located thereto to hold the web holders down to their work, cam means 10 for operating the sinkers, said sinkers extending between and being guided by the said bits or pieces, substantially as described.
- 15 15. In combination spring beard needles, web holders, a bed having a machined upper surface for guiding the web holders, bits or pieces held stationary by but removable from the bed and extending between the web holders to guide them, sinkers interlocking with the web holders for operating them, cam means for operating the sinkers, said sinkers extending between and being guided by the said bits or pieces, said bits, or pieces providing presser surfaces for the needle beards, and means for deflecting the 20 needles for pressing, substantially as described.
- 25 16. In combination spring beard needles, web holders, a web holder bed, bits or pieces held by said bed removably and extending up therefrom to furnish guidance for the web holders, sinkers also guided by said bits or pieces, said bits or pieces furnishing presser surfaces for the needle beards, substantially as described.
- 30 17. In combination spring beard needles, web holders, a web holder bed, bits or pieces held by said bed removably and extending up therefrom to furnish guidance for the web holders, sinkers also guided by said bits or pieces, said bits or pieces furnishing presser surfaces for the needle beards, substantially as described. 45
18. In combination spring beard needles, a web holder bed, web holders, presser bits held removably by the web holder bed to press the needle beards, said presser bits serving to guide the web holders, sinkers pivotally mounted, said web holder bed having an extension to furnish a bed for the sinkers and having pivot bearings therefor, substantially as described. 50
19. In combination in a knitting machine, a needle carrier, needles, a bed, web holders, and pieces removably mounted on the bed for guiding the web holders, each of said pieces having a pair of prongs with a space between and frictionally and removably engaging seats on the bed, substantially as described. 55
20. In combination, web holders, a bed having a surface upon which the web holders move and removable walls for guiding the web holders, said bed being slotted and the said removable walls being of inverted U-shape with their prongs embracing the bed, substantially as described. 60
21. In combination, web holders, a bed therefor, slotted across its top and along its vertical side, and removable walls seated in said slots, the web holders being removable independently of the said walls, substantially as described. 70
- In testimony whereof, I affix my signature. 80

FRANK WILCOMB.
